UNITED STATES PATENT OFFICE.

J. FREEMAN MCKENNEY, OF BALTIMORE, MARYLAND.

SEWING-MACHINE TAKE-UP.

SPECIFICATION forming part of Letters Patent No. 403,951, dated May 28, 1889.

Application filed August 30, 1886. Serial No. 212,188. (No model.)

To all whom it may concern:

Be it known that I, J. FREEMAN MCKENNEY, a citizen of the United States, residing at Baltimore, in the State of Maryland, have invented 5 certain new and useful Improvements in Sewing-Machine Take-Ups, of which the following is a specification.

My invention relates to an improved take-up for sewing-machines. The construction 10 of the parts which co-operate to accomplish the desired result of taking up the slack thread will be described in connection with the accompanying drawings, which illustrate several forms of carrying the invention into 15 effect.

Figure 1 is a perspective view of the arm, needle-bar, and work-plate of a sewing-machine, showing an application of the take-up. Fig. 2 is a central vertical section showing the 20 needle-bar and take-up. Fig. 3 is a front view of the sewing-machine arm, showing the take-up and the position of the thread. Fig. 4 is a horizontal section of the head, showing the operating mechanism. Figs. 5 and 6 are views 25 of the take-up plate, and serve to aid a description of the different positions of the thread at different points of stroke of the needle-bar. Figs. 7 and 8 are two views showing a modification of the take-up, the change 30 consisting in a reversal of the position and movement of the parts shown in Figs. 1 to 6. Figs. 9 and 10 are two views showing another 35 modification of the take-up, (the parts operating the same as those shown in Figs. 1 to 6,) the change consisting in dispensing with the slot in the head and having the thread-eyes attached to a downwardly-depending arm.

The letter A designates the overhanging arm of a sewing-machine; A', the needle-bar 40 head at the end of said arm; B, the needle-bar, which has bearing and vertical movement in the arm; C, the needle; D, the work-plate; D', the presser-bar; E, the cam-plate on the needle-bar; F, the crank-wheel which 45 acts on the said cam-plate, and F' the shaft on which the crank-wheel is mounted. All of these parts are of the usual or well-known construction, and are here shown merely to aid in arriving at an understanding of the 50 invention.

The improved take-up consists, essentially, of two parts: first, a thin plate of suitable

material having the contour of one edge shaped to form a special curve, or instead of the thin plate an equivalent device would be 55 a wire bent to produce the desired curve; and, second, an arm forked or bifurcated, and each fork provided with a thread-eye and arranged so that each of the two forks should take position on an opposite side of the said curved 60 plate or wire. Instead of an arm with two forks, two separate arms may be used, and one of said parts be stationary, while the other is movable.

The improved take-up comprises, as stated, 65 two parts, one of which is the plate G, having at the top and front an outwardly-curved edge, h, which is substantially the arc of a circle. This plate is broadest at that part, h', which is in a horizontal line drawn from a 70 point, 2, which is concentric with said arc of a circle. Below the broadest part, h', the plate has an inward curve, h², which extends down to the narrowest part, h³. The other part of the take-up is the arm I, with the two 75 thread-eye forks k, one of which is on each side of the plate. The eyes are designated by the letter l. The front face of the head A' in Figs. 1 to 4 has a vertical slot, m. The arm I, having the two forks k, is attached in 80 any suitable manner to the movable needle-bar B, and the two forks project through the said slot m in the front of the head.

The plate G is secured in a vertical position to the front of the head A', and projects 85 therefrom edgewise and extends lengthwise of the slot in the head, and is between the said two thread-eye forks k. A stationary thread-eye, n, is located at a suitable position. In this instance it is on the face of the head 90 near the point whereat the vertically-movable forks k reach their lowest position. The thread a passes through the stationary eye n, then through the eye l of each fork, and cross-wise of the curved edge of the plate which is 95 between the two forks, and thence to the eye of the needle C. While the position of the stationary thread-eye n may be varied on the sewing-machine head, this variation must be within certain defined limits. It is essential 100 to the proper and best action of the take-up that this stationary thread-eye should never be located above the plane of the extreme downward limit of travel of the movable

thread-eyes carried by the needle-bar; but it may be located either at said downward limit or below said limit. The thread passing over the take-up plate should never pass below the 5 stationary thread-eye, since it is essential that during the upward movement of the thread-eyes on the needle-bar the slack in the thread should be taken up by the action of the take-up plate, and this can only be accomplished by having the stationary thread-eye or thread-guide at or below the lower limit of travel of the thread-eyes on the needle-bar, since otherwise there would be slack thread between the stationary eye and the 10 movable thread-eyes during the first portion of the upward movement of the needle-bar, which would prevent the proper operation of the take-up. By this arrangement the two forks *k*, through which the thread passes, are 15 movable, and the plate with the curved edge is stationary. The relative position of these two parts, however, may be reversed—that is, the forks may be stationary and the plate movable, as in Figs. 7 and 8.

25 In the present instance the thread-eye forks *k* of the take-up are shown attached directly to the needle-bar; but inasmuch as the cam-plate *E*, fixed on the needle-bar, is "a movable part," it is obvious that "the thread-eye forks" may be attached to the said cam-plate and project therefrom at each side of the needle-bar.

The distinguishing feature of this invention is in the plate having at the top and front 30 the special outward curve, *h*, forming substantially the arc of a circle. In the descent of the needle-bar the thread-eye forks *k*, from the point 1, (see Fig. 5,) keep the thread drawn taut over the plate-edge at the top curve, *h*, 35 and this taut condition continues until the thread-eyes pass below the point 2, which is concentric with the said top curve, at which time the point of the needle will have penetrated the material to be sewed. Up to this 40 time the thread over the top curved edge has been gradually slipping down around the curve; but all the while the thread has been held up, and thereby the formation in it of a loop which would interfere with the needle 45 has been prevented. When the thread-eye forks *l* in the downward movement reach the inward curve, *h*², at the point 3, the thread has become slack and at this moment is in condition for the shuttle to pass between it 50 and the needle. Upon the needle-bar, with the eyes at the point 4, (see Fig. 6) beginning to ascend after the shuttle has passed the slack-thread is taken up by the thread-eyes (beginning at the point 5) drawing the thread up 55 in contact with the inward curve, *h*², and this taking up continues until the thread on the plate-edge passes the broadest part, *h*¹—say, at the point 6—at which time, also, the shuttle has completed its forward movement and 60 the stitch is being drawn to its full tension.

In Figs. 7 and 8 the two take-up parts—to wit, the special-shaped plate *G* and the two

thread-eye forks *k*, one on each side of the plate—are reversed. The plate *G* has the outwardly-curved edges *h*, which forms the arc of 70 a circle at the bottom instead of the top, and instead of being stationary, as in Figs. 1 to 4, it is attached to the needle-bar *B* and is therefore movable. On the other hand, the two forks *k* are secured to the front of the 75 head *A'*, and are therefore stationary. The shape of the plate *G* in this case being the same as before described, the result is the same. The threading is a little different. Here the thread *a* passes through a hole, *q*, 80 in the top of the needle-bar and then down through the thread-eyes *l*.

In Figs. 9 and 10 the plate *G* is stationary and the thread-eye forks *k* are movable—same as in Figs. 1 to 4. There is no slot in the 85 front face of the head. This is rendered unnecessary, because each thread-eye *l* is at the lower extremity of a downwardly-depending arm, *k*, whose upper end, *k'*, is attached to the needle-bar *B* at a point above head *A'*. The 90 operation is the same as the construction shown in Figs. 1 to 4.

Having described my invention, I claim and desire to secure by Letters Patent of the United States—

95

1. In a sewing-machine embracing a head having a front face provided with a vertical slot, *m*, a needle-bar, and a shuttle, the combination therewith of the take-up, consisting of two forks, *k*, attached to the needle-bar 100 and each provided with a thread-eye, and a plate, *G*, having at the top and front an outwardly-curved edge, *h*, forming substantially, the arc of a circle whose lower portion terminates at the broadest part of the plate and having below said broadest part an inward curve, *h*², said plate extending lengthwise of the vertical slot and having position between the said two thread-eye forks, as set forth.

2. In a sewing-machine, the combination, 110 with the needle-bar and shuttle, of a take-up, one part thereof consisting of two forks, *k*, each provided with a thread-eye, and another part consisting of a plate, *G*, having at one end a front outwardly-curved edge, *h*, forming, substantially, the arc of a circle, one portion of which terminates at the broadest part of the plate and having an inward curve, *h*², 115 said plate extending vertically and having position between the said two thread-eye forks, one of said parts being movable and the other stationary, as set forth.

3. In a sewing-machine, the stitch-forming mechanism thereof, in combination with a take-up, one part thereof consisting of two 125 thread-eyes and another part consisting of a plate between said thread-eyes, said plate having a cam-shaped outer edge curving inwardly both above and below its broadest part, one of said parts being movable and the other stationary, substantially as set forth.

4. In a sewing-machine, the stitch-forming mechanism thereof, in combination with a take-up, one part thereof consisting of two

130

thread-eyes and another part consisting of a plate having at one end an outwardly-curved inclined edge, forming, substantially, the arc of a circle, one portion of which terminates at 5 the broadest part of the plate and having an inward curve, said plate extending vertically and having position between the said thread-eyes, one of the said parts being movable and the other stationary, substantially as set forth.

10 5. In a sewing-machine, the head and stitch-forming mechanism thereof, the needle-bar of said stitch-forming mechanism, and two thread-eyes carried by said needle-bar, in combination with a stationary take-up plate located vertically between said thread-eyes, said plate having its outer edge curved or cam-shaped, the upper portion of said edge being curved downwardly and outwardly and terminating at the broadest part of said plate,

15 and the lower portion of said edge curving from the broadest part of the plate downwardly and inwardly, substantially as set forth.

6. In a sewing-machine, the head and stitch-forming mechanism thereof, the needle-bar of 25 said stitch-forming mechanism, and a take-up consisting of two thread-eyes carried by said needle-bar and of a stationary plate extending vertically between said thread-eyes, said plate having its outer edge cam-shaped and 30 curving inwardly both above and below its broadest part, in combination with a stationary thread-eye on the sewing-machine head, through which the thread passes before passing through said thread-eyes on the needle-bar, said stationary thread-eye being located at or below the extreme downward limit of travel of said thread-eyes on the needle-bar, 35 substantially as set forth.

In testimony whereof I affix my signature in 40 the presence of two witnesses.
